UNITED STATES PATENT OFFICE

MIHRAN M. DOLMAGE, OF WASHINGTON, DISTRICT OF COLUMBIA

NEGATIVE RESISTANCE

Application filed January 13, 1927. Serial No. 160,978.

This invention covers a new method for obtaining a negative resistance which is automatically variable within predetermined limits, increasing or decreasing in a definite manner, as may be required, with an increase in the outside electromotive force impressed upon the electrical network having the above defined negative resistance characteristics. I have shown in U. S. A. Patent No. 1,606,350, 10 how an arrangement of apparatus can be realized which will have a constant negative resistance characteristic, independent of frequency within the practical limits of a few hundred cycles to about a million cycles per second. Where a negative resistance is used for the purpose of obtaining a constant load upon an electric generator with an actually varying line impedance (for a specific application reference may be made to U. S. A. 20 Patent No. 1,606,350 granted to me, relative to impedance variation compensator circuits) I find greatly improved results can be obtained if the negative resistance instead of being constant should vary with the electromotive force impressed upon it in a definitely predetermined manner, as fully explained hereunder in these specifications.

The novel features of my invention I have pointed out in my claims. The invention 30 itself will be best understood as to its construction and method of operation, together with further objects and advantages by reference to the following description taken in connection with the drawings.

Figure 1 shows one form of the invention. Figure 2 is a modification thereof. Figure 3 is a diagram for illustrating certain features of the operation of the invention.

In Fig. 1 of the drawings the combination 40 of apparatus connected to terminals 1 and 2 to the right of the drawings represents a negative resistance having the particular characteristics fully described in these specifications and shown graphically in Fig. 3 of the drawings. Connected to terminals 1 and 2 by dotted lines, are the terminals of an alternating source 20 in series with impedance 19. Impedance 19 includes the internal impedance of the generator and such additional 45 impedance as service requirements might de-

mand. As an illustration, the alternating current source 20 may be working over a given transmission line, in which case impedance 19 would represent the impedance of the transmission line as seen from terminals 1 and 2, under given operating conditions. Across terminals 1 and 2 are connected primary windings 3 and 5 of transformer A through impedance 7. Primary winding 10 of the input transformer B of the amplifier 55 bulb 14 is connected to terminals 8 and 9, as shown, through resistance 15. The secondary winding 11 of this input transformer is connected to the potentiometer 12 which is in turn wired across the grid and filament 60 circuit of the amplifier through the grid biasing battery 13. The plate circuit of amplifier bulb 14 is connected through a suitable plate battery to the secondary windings 4 and 6, which have as primary windings 3 65 and 5, respectively.

The system shown on Fig. 1, wired as just described, consists broadly of a network in which a given electromotive force (that of alternating current source 20) is amplified 70 and reimpressed back upon the same network so that, in general, there will result an increased flow of current in the circuit of alternating current source 20 and impedance 19. The arrangement will be made clearer by the 75 following description of the method of operation of the system. Electromotive force E of alternator (20) forces a current through the transmission line (represented schematically by impedance 19) and winding 3 of transformer A. If the impedance of the input circuit, as measured from terminals 8 and 9, is made equal to the impedance of the plate circuit as seen through primary winding 3 when resistance 7 is equal to infinity 80 ohms, then there will be no initial current flow through resistance 7, even when the circuit of resistance 7 is closed. This is a result of the balanced Wheatstone bridge arrangement of the circuit shown on Fig. 1 85 of the drawings. Under the above mentioned assumed conditions this initial current is amplified by bulb 14 and reimpressed back through primary windings 3 and 5 upon the outside circuit represented by generator 20 90

and impedance 19. Impedance 7 can be so chosen with reference to impedance 19 that no amplified current will flow through the input circuit and the negative resistance network represented by the combination of apparatus connected to terminals 1 and 2, as shown in full line, will then be working under conditions of maximum stability. This condition of maximum stability is obtained when, 5 for instance, windings 3 and 5 are of equal number of turns and of equal impedance, the corresponding secondary windings 4 and 6 bear the same equality relations to each other, and impedance 7 is exactly equal to impedance 19.

10 The numerical value of the negative resistance may be changed within very wide limits by a change in the adjustment of the potentiometer without it being necessary to make any other changes in the network. The wide 20 range of adjustment possible with the system described in these specifications will also be clear if it is realized that, by a proper shifting of the potentiometer, the amplified 25 electromotive force may be so regulated, that there will be no current flow whatever through source 20 or winding 3. Conversely, if the wires between bulb 14 and secondary windings 4 and 6 are reversed, the potentiometer of the amplifier can again be so adjusted that the impedance of the combination 30 of apparatus connected to terminals 1 and 2 will be numerically equal to zero. These 35 rather two interesting and striking applications will be made clear by reference to the formulæ, giving the values of the negative resistance of the network as indicated hereunder.

40 The system herein described differs physically in no essential parts from the system disclosed in U. S. A. Patent 1,606,350, granted to me. It differs, however, in this outstanding feature, viz. that the plate battery and the grid battery are so chosen with respect to each other, and further the load impedance of the vacuum tube is also so chosen, 45 that this vacuum tube operates as a detector-amplifier combination instead of being arranged to operate as a pure amplifier which is the arrangement utilized in U. S. A. Patent 1,606,350 granted to me above referred to. The valuable features obtained by means of the above essential difference will be made very clear hereunder. Be it noted first that 50 two main points must be properly cared for before a detector-amplifier arrangement, such as referred to above, can be realized.

55 1. The grid-volts and plate current characteristic must remain curved and not straightened out into linear relationship with respect to each other. As is well known, this characteristic becomes linear with the inclusion of an impedance in the plate circuit at least equal to the impedance of the plate-filament vacuum path. The choice in the rela-

tive number of turns of primary and secondary windings of transformer A included in the plate circuit must, therefore, be so made that the impedance of the outside circuit connected to the plate-filament path will be small 70 compared with the resistance r_p of the plate-filament circuit itself.

2. The value of the equivalent voltage

$$\frac{E_p}{\mu} + E_g + \epsilon \quad 75$$

must be numerically smaller than E_f , where E_f is the filament voltage and

E_p = Effective voltage available between filament and plate.

μ = Amplification constant of the vacuum tube.

E_g = Voltage between grid and filament.

ϵ = Contact potential, usually not exceeding 85 0.50 volts between the materials forming the plate and the filament respectively.

To show very clearly the effect of the use of a detector-amplifier combination, instead of a pure amplifier, we will first assume for the circuit arrangement of Fig. 1 of the present drawings that the dynamic characteristic has been straightened out and that the varying portion of the current in the plate circuit is given by the first term only in Equation (12).

Let us call

V = Electromotive force of an alternating current generator having no internal 100 impedance connected to terminals 1 and 2 of the negative resistance, as shown on Fig. 1 of the drawings.

i_1 = Current through primary winding 10 of transformer A.

i_2 = Current through primary winding 3 and element 7.

A = Series resistance of grid circuit of amplifier 14 as measured through primary winding 10 and of the resistance 110 15 in series with said winding.

B = Series resistance of plate circuit as measured through either winding 3 or winding 5, with the other winding and its corresponding secondary open.

Y = Resistance of element 7.

Y_1 = Resistance of element 19.

N_1 = Ratio of terms of winding 11 to winding 10.

N_2 = Ratio of turns of winding 3 to winding 4, or similarly, winding 5 to winding 6.

R_2 = Resistance of grid circuit as measured through winding 10.

K = Coefficient having a value less than, or equal to unity, depending upon the position of the potentiometer.

$$a = \frac{1}{4A} \frac{R_2 K \mu N_1}{N_2} \quad 860$$

The equations governing the performance of the circuit are as follows:—

$$(1) \quad V = B(i_1 + 2i_2) + Ai_1 + \frac{V'}{N_2}$$

$$(2) \quad V = B(i_1 + 2i_2) + \frac{V'}{N_2} +$$

$$B(i_1 + 2i_2) + \frac{V'}{N_2} + Yi_2$$

$$(3) \quad V' = Ai_1 K \mu N_1 \frac{R_2}{A} = 4aAi_1(N_2)$$

The derivation of V' will be clear if it is borne in mind that the potential across the terminals of winding 10 is equal to R_2i_1 , the corresponding secondary potential is equal to $N_1R_2i_1$ which is reduced by the potentiometer to the value $KN_1R_2i_1$. The equivalent alternating current potential in the plate circuit is obviously given by—

$$V' = \mu KN_1 R_2 i_1$$

Introducing the value of V' , obtained from Equation (3) into Equations (1) and (2), the following two relations are obtained between V , i_1 , and i_2 :

$$(4) \quad V = (A + B + 4aA)i_1 + 2Bi_2$$

$$(5) \quad V = (2B + 8aA)i_1 + (4B + Y)i_2$$

The solution of the above two simple equations gives for (i_1) and (i_2)

$$(6) \quad i_1 = V \frac{(2B + Y)}{(B + A(1 + 4a)) \{4B + Y\} - 2B \{2B + 8aA\}}$$

$$(7) \quad i_2 = V \frac{A - B - 4aA}{(B + A(1 + 4a)) \{4B + Y\} - 2B \{2B + 8aA\}}$$

The common denominator in the above two fractions can be further simplified into

$$B(4A + Y) + AY(1 + 4a)$$

The total current $(i_1 + i_2)$ into the negative resistance network is given by

$$(8) \quad (i_1 + i_2) = V \frac{A(1 + 4a) + B + Y}{B(4A + Y) + AY + 4aAY}$$

The total resistance offered by the circuit arrangement shown on Fig. 1 of the drawings is evidently equal to

$$(9) \quad \frac{V}{i_1 + i_2} = \frac{V}{i_1 + i_2}$$

or

$$(9) \quad \frac{V}{i_1 + i_2} = \frac{B(4A + Y) + AY + 4aAY}{A + B + Y - 4aA}$$

In Fig. 1 of the drawings a single amplifying-detecting unit is shown. It is clear that a number of such units could be used in series and secure thereby as large a value for (a) , as we please. It will be noted, first, that

when (a) is sufficiently small so that the denominator of Equation (9) is positive in value, the resistance offered by the network to alternating currents is also positive. In order that the network should act as a negative resistance as intended, we must make

$$A + B + Y - 4aA < 0$$

or

$$a > \frac{A + B + Y}{4A}$$

It will be also noted that when (a) is given its critical value

$$a = \frac{A + B + Y}{4A}$$

then the resistance offered to the passage of attenuating currents is infinity. For values of (a) greater than the critical value indicated above, we have a negative resistance. With a further increase in the value of (a) a decrease in the absolute value of the negative resistance results. The asymptotic value below which the absolute value of the negative resistance cannot go, no matter how large a value (a) may have, is given by $(-Y)$. If, however, the wiring between the plate and the secondary windings (5) and (6) is reversed, we get a new range of negative resistances. This reversal is equivalent to the changing of (a) into $(-a)$ in Formula (8). With this change in the formula, we see immediately that in order to obtain a negative resistance characteristic, we must choose for (a) , a value such that

$$B(4A + Y) + AY - 4aAY < 0$$

or

$$a > \frac{B(4A + Y) + AY}{4AY}$$

The lowest critical value of (a) which will provide a negative resistance characteristic, is given by

$$(11) \quad a = \frac{B(4A + Y) + AY}{4AY}$$

One of the very interesting and important applications of the present invention may be briefly referred to here. If (a) is given its critical value as indicated by Formula (11), the network shown in Fig. 1 of the drawings is a short circuit for a very large range of alternating current frequencies, while offering a definite resistance to direct currents.

It may be noted here that for any given value of (a) , a constant negative resistance is obtained regardless of the value of the resistance of the outside circuit represented by element 19. To secure proper operation, it is sufficient that the unbalance between elements 19 and 7 should not exceed a definite

limit. If this limit is exceeded the stability of the network would be destroyed. This point has been carefully reviewed in my U. S. A. Patent No. 1,606,850 and will not be referred to further here. In the derivation of all the preceding formulæ the assumption is that the amplifier bulb 14 is operating as a pure amplifier. As already noted hereinabove in this specification, the essential characteristics of the present invention are mainly two—

- (1) The amplifier bulb (14) is arranged to function as an amplifier-detector combination and not as a pure amplifier.
- (2) The load upon the plate circuit is sufficiently low in impedance so that the characteristic of the grid-volts and plate-current curve will be represented by a curve rather than by a straight line.
- With regard to the first point, reference may be made here to the following relation which gives the value of the variable portion of the current in the plate circuit, for the general case, which is

25

$$(12) \quad J = \frac{\mu e}{r_p + r_o} - \frac{1}{2} \mu^2 \frac{r_p r' p}{(r_p + r_o)^3} e^2 - \dots$$

where

e = Alternating current electromotive force impressed upon the grid.

r_p = Resistance of plate-filament path to alternating current.

$r' p$ = The first derivative of the alternating current resistance with respect to E_p .

(For proof of above relation—see Van der Bijl—Thermionic Vacuum Tubes, page 317, Formula 8.)

The first term is the alternating current component of frequency p in the plate circuit. The second term is proportional to e^2 . If $e = e_0 \sin pt$, then $e^2 = e_0^2 \sin^2 pt$. Replacing $\sin^2 pt$ by its equivalent

45

$$\sin^2 pt = \frac{1 - \cos 2pt}{2},$$

the second term may be written in the form

50

$$(13) \quad J_2 = -\frac{1}{4} \mu^2 \frac{r_p r' p}{(r_p + r_o)^3} e^2 - \frac{1}{4} \mu^2 \frac{r_p r' p}{(r_p + r_o)^3} e^2 \cos 2pt$$

The first term in the above formula represents a direct current component. We are primarily interested in this component and we find that this direct current component can be used so that certain definite variations will result in the value of the negative resistance obtained by means of the arrangement of apparatus shown on Fig. 1 and Fig. 2 of the drawings, as will be indicated hereunder.

Since, as shown in Formula (13), the in-

crease in the direct current through the plate circuit is inversely proportional to

$$\left(\frac{1}{r_p + r_o} \right)^3,$$

it is evident that to obtain the best results possible for the specific purpose we have in mind, we should make r_o as small as possible with reference to r_p . One of the essential requirements to secure proper operation of bulb (14) as an amplifier-detector combination consists in a choice for the value of E_b for the plate battery such that

$$(14) \quad \frac{E_b}{\mu} + E_g + e < E_f \quad 23$$

It must be also clear that Equation (12) is valid, provided (e), the alternating potential imposed upon the grid of bulb (14), satisfies the equation—

$$(15) \quad \frac{E_b}{\mu} + E_g + e + e < E_f \quad 25$$

When vacuum tube (14) is working under the conditions which have been specified above, the resistance of the plate-filament circuit will vary in a definite manner, depending upon the value of the electromotive force (e) instead of remaining a constant or very nearly a constant. Referring, therefore, to Equation (9) which can still be used to determine the numerical value of the negative resistance of the network as measured between terminals (1) and (2), we note that B in said equation

instead of being a definite constant varies with (e) as just stated. It follows necessarily that the negative resistance of the electrical network itself as described in these specifications will also vary. It will vary in a predetermined manner, as a definite function of (e). Such a variable negative resistance—varying in a definite manner as a function of the electromotive force imposed upon it, has certain very definite and valuable uses in the electrical art. To show in a more concrete manner how and to what extent a variation in the negative resistance may be secured, for a given fixed setting of the potentiometer of the amplifier bulb (14), we will consider an amplifier having the grid volts-plate current characteristic, as indicated in the following table:

$E_b = 130$ volts (plate battery)

$E_g = -9$ volts (grid battery)

$I_b = 8$ mils (plate current)

$E_f = 4.4$ volts (filament volts)

$\mu = 6$

We will analyze hereunder the performance characteristics of the above tube and show the effect of the use of such a tube in the circuit of Fig. 1 of the drawings as element (14). We are concerned here with the

variation of r_p . Since, by definition, r_p is given by the relation

$$(16) \quad r_p = \frac{dE_p}{dI_p}$$

and since vacuum tubes follow the general law

$$I_p = \alpha E_p^n$$

it follows that

$$10 \quad \frac{1}{r_p} = \frac{dI_p}{dE_p} = \alpha n E_p^{n-1} = \frac{nI_p}{E_p}$$

Hence

$$(17) \quad r_p = \frac{E_p}{nI_p}$$

15 It also follows that r'_p , which expresses the variation in the plate-filament resistance for a small change in the effective potential E_p between plate and filament, is given by

$$20 \quad r'_p = \frac{dr_p}{dE_p} = \frac{1}{n} \frac{I_p - E_p r_p}{I_p^2}$$

In the case of most vacuum tubes, operated 25 in the ranges now considered most effective in practice, n is approximately 2. The value of r'_p is therefore equal to, approximately

$$r'_p = \frac{1}{n} \frac{I_p - nI_p}{I_p^2} = \frac{1-n}{nI_p}$$

30 Since, further

$$\frac{1}{I_p} = \frac{nr_p}{E_p}$$

it follows that

$$35 \quad (18) \quad r'_p = \frac{1-n}{n} \times \frac{nr_p}{E_p} = (1-n) \frac{r_p}{E_p}$$

In the case of the tube chosen above

$r_p = 6000$ ohms

40 $n = 1.6$ approximately

$E_p = 130 - 6 \times 9 = 76$ volts

Hence

$$45 \quad r'_p = - \frac{6}{10} \frac{6000}{76} = -48 \text{ ohms approximately}$$

For each increase of one volt in E_p , the plate-filament circuit resistance decreases about 48 ohms, provided the increase in plate filament voltage is comparatively small in 50 amount.

55 Referring to the characteristic of the tube, assuming that the alternating potential (e) is equal to 0 volts, we find that the instantaneous current in the plate circuit is equal to 28 mils. For this value of grid potential the value of

$$r_p = \frac{E_p}{nI_p} = \frac{130 - 54}{1.6 \times 0.008} = 6000 \text{ ohms}$$

60 The next problem consists in the determination of the value of the "detected" direct current J_d which is the direct current component of J_2 . This current depends upon r_p and r'_p , which in turn depend upon the same component, so that derivation of J_d is some-

what complicated. To simplify the problem, we will neglect as a first approximation, the effect of the potential drop $r_o J_d$ in the expression for E_p

$$70 \quad E_p = E_b + \mu E_g - r_o J_d$$

where

r_o = Resistance of plate circuit load

J_d = Direct current component of J_2 .

75

When the above assumption is made and we take for r_o , the value equal to

$$\frac{r_p}{10}$$

80

Then (by Formula 13)—

$$J_d = - \frac{1}{4} \times 36 \times 100 \times \frac{r'_p}{1.32 r_p^2}$$

85

We have also shown

$$r'_p = \frac{(1-n)}{n} \times \frac{r_p}{E_p} = \frac{1-n}{n} \frac{1}{I_p}$$

$$r_p = \frac{E_p}{nI_p}$$

90

Hence, substituting these values of r'_p and r_p into the value of J_d as given above, we obtain

$$J_d = - \frac{900n(1-n)I_p}{1.32E_p^2}$$

100

Obviously

$$I_p = I_b + J_d$$

Therefore

$$J_d = \frac{0.113 \times 8}{0.897} = 1 \text{ milli ampere approx.}$$

105

The values of r'_p and r_p can now be determined more accurately by substitution of the above value of J_d into the formulae relating together these quantities. Such a substitution when carried out, results in a value for $r'_p = -41$ ohms and for $r_p = -5237$ ohms.

110

The comparison is therefore as follows: 115 When the alternating current electromotive force (e) is absent, the vacuum tube resistance is equal to 6000 ohms. When the electromotive force (e) is equal to ten volts, the tube resistance drops down to 5237 ohms. 120 It is this variation which it is proposed to utilize. A specific design was worked out in full detail to indicate the extent of the variation obtainable in the negative resistance network with a specific type of vacuum tube. A 125 similar method may be used with any other type of vacuum tube.

The law relating together the negative resistance of the electrical network shown on Figure 1 of the drawings may now be derived 130

in its general form, as follows. The plate resistance is given by, as shown

$$5 \quad r_p = \frac{1}{n} \frac{E_p}{I_p} = \frac{1}{n} \frac{E_p}{I_b + J_d}$$

Since, as indicated above,

$$10 \quad (19) \quad J_d = C e^2 (I_b + J_d)$$

$$J_d = \frac{C I_b}{1 - C e^2} e^2$$

Where C = constant, depending upon the tube used, and the plate battery voltage, etc. Using the above expression for J_d , we obtain the following general expression for

r_p —

$$20 \quad (20) \quad r_p = \frac{E_p}{n I_b} (1 - C e^2)$$

which is approximately correct within a few per cent, and is quite general in type. In the case of the tube for which a detailed design was given above C is found equal to .00127. It will naturally vary with the particular type of vacuum tube used.

In order to simplify the expression for r_p , as given in Formula (20), we can write it in the form

$$30 \quad r_p = C_o - C_1 e^2$$

a relation which indicates definitely and clearly the law of variation of r_p with (e) . If we now refer to Formula (9) which gives a value of the negative resistance network, we note in that formula the symbol B which is equal to

$$35 \quad (21) \quad B = N_2^2 \times r_p = N_2^2 (C_o - C_1 e^2)$$

The operation of the detecting-amplifying system as described in some detail hereinabove was outlined on the basis that the amplifying constant of vacuum tube (14) was non-varying. It is known, however, that this constant does vary to some extent with both the plate and grid batteries, increasing with increase in the absolute value of both the plate battery and the grid battery. It has lately been found that this varying value for the amplification constant results in the production of the larger amount of second harmonic current than previously derived on the basis of the assumption of a constant value for the amplification constant. Since the direct current produced in the plate circuit and the second harmonic current are numerically equal to a first degree of approximation (see Formula 13 of the present application) it follows that the corresponding change in the tube resistance would also be somewhat in excess of the value obtained, using Formula (18) of the present specification.

It may be of interest here to also note that the effect of a change in the value of the tube resistance upon the value obtained for the

negative resistance network terminating at terminals 1 and 2 of Fig. 1 of the drawings, depends upon the mode of connection between the plate circuit and secondary windings 4 and 6. Without going into all of the details in the mathematical development it may be shown that for a small increment in the value of tube resistance, the increment in the current flowing through the negative resistance network, as wired to terminals 1 and 2 of Fig. 1 of the drawings, is proportional to

$$70 \quad \{8aA - 2A - Y\} \{2A + Y\}$$

It is therefore clear that if constant (a) is greater than

$$80 \quad \frac{2A + Y}{8A},$$

then an increase in the value of tube resistance (B) will result in an increase in the value of the current flowing through the network. On the contrary if the wire connections between the plate circuit and transformer windings 4 and 6 are reversed, which is equivalent to changing the sign of (a) in the above formula, then any increase in the value of the tube resistance (B) will result in a decrease in the value of the current flowing into the network wired at terminals 1 and 2 of Fig. 1 of the drawings.

As already discussed in detail, we see that a number of interesting and important applications are possible where a plate resistance varying as shown in Formula (21) is available. For instance, suppose we place the negative resistance in series with a load receiving its power through impedance (19) from generator (20), and so chose (a) that for a normal voltage (V) upon said load the negative resistance represented by the network shown on Figure 1 of the drawings, is zero in value. Should a change now occur in the load, the negative resistance will tend to maintain constant the potential across the load. For proof, if the load decreases in resistance, the potential (V) , available across the terminals of the grid increases; this increase will result in a decrease of the resistance offered by the network from zero ohms to some negative value. The total drop in potential between the terminals of the generator source and the load will therefore tend to decrease, and consequently, the potential across the load will tend to remain constant. In this case, therefore, the combination of apparatus designated as a variable negative resistance will act as an automatic potential regulator. It is sufficient and necessary for this purpose that the circuit between the plate and transformer windings 4 and 6 should be as exactly shown on the drawings. If the circuit were to be reversed, potential regulation cannot be obtained.

The arrangement shown in Figure 2 of the drawings consist of two networks of the type

shown in Figure 1, working on the so-called "push-pull" basis. When the variable negative resistance as described in these specifications is used in a telephone circuit, it tends to produce harmonics. These have a detrimental effect upon quality, as well known. The arrangement of Figure 2 eliminates the harmonics in the outside circuit. Figure 3 of the drawings show the variation obtained in the value of the negative resistance with a change in amplification.

The electrical network described in these specifications is a negative resistance independent of frequency, since its value is given by Formula (9), in which A and B are either pure resistances (or can be made to represent pure resistances through devices well known to the art). It may therefore be used for high as well as low frequencies. It may be adjusted within extremely wide limits as already shown in the detailed description given hereinabove. The electrical network described herein furnishes a negative resistance which stays fixed in value, even though the resistance of outside circuits changes, provided the amplifying power of the amplifying circuit included in said network remains constant and provided further the initial potential imposed upon its terminals remains constant. It is stable and non-oscillating in character.

The uses to which a negative resistance, as hereinbefore specified, may be put are so many that no attempt will be made to give even a partial list of such uses. An important application consists in its use in the main antenna circuit of a radio receiving system. A second very important application consists in the possibility it affords to compensate line impedance variations in telephone repeater systems, thereby allowing greater amplification. A third important application consists in its use as a line reflection reducing device when used in conjunction with an impedance compensator circuit. A fourth application consists in its use as an automatic potential regulator, substantially as described.

A further important application of the arrangements described in the present specifications is in conjunction with impedance variation compensator circuits, which are described in my pending application S. N. 358,370. When such a combination is used, it is possible to obtain repeater amplifications in two-way telephone systems, under variable line conditions, far in excess of those possible in the art at the present time.

What I claim:

1. An electrical network, means to connect said network to an outside circuit, a detecting-amplifying system in said network, and means to superimpose upon said outside circuit the electromotive force of the final output circuit of said amplifying system in combi-

nation with means to prevent said electromotive force from being impressed upon the input circuit of said amplifying system.

2. An electrical network, means to connect said network to an outside circuit, a detecting-amplifying system in said network, means to vary the amplification of said system, and means to superimpose upon said outside circuit the electromotive force of the final output circuit of said amplifying system, in combination with means to prevent the said electro-motive force from being impressed upon the input circuit of said amplifying system.

3. An electrical network having a negative resistance independent of frequency, means to connect said network to an outside circuit, a detecting-amplifying system in said network, and means to superimpose upon said outside circuit the electromotive force of the final output circuit of said amplifying system.

4. An electrical network having a negative resistance independent of frequency, means to connect said network to an outside circuit, a detecting-amplifying system in said network, means to prevent the "singing" of said amplifying system, and means to superimpose upon said outside circuit the electromotive force of the final output circuit of said amplifying system.

5. An electrical network having a negative resistance independent of frequency, means to connect said network to an outside circuit, a detecting-amplifying system in said network, means to vary the amplification of said amplifying system, and means to superimpose upon said outside circuit the electromotive force of the final output circuit of said amplifying system.

6. An electrical network having a negative resistance independent of frequency, means to connect said network to an outside circuit, a detecting-amplifying system in said network, means to prevent the "singing" of said network, means to vary the amplification of said amplifying system, and means to superimpose upon said outside circuit the electromotive force of the final output circuit of said amplifying system.

7. In combination, a bridge circuit containing a detecting-amplifying system with its initial and final output circuits occupying opposite arms, an outside circuit and a balancing network also occupying opposite arms in said bridge, an electromotive force in said outside circuit, and means to superimpose upon said outside circuit the electromotive force of the final output force of said amplifying system.

8. A two-terminal electrical network, including a detecting amplifying system in said network with mutually non-reacting input and output circuits, both connected to said terminals, with the amplification of said am-

plifying system adjusted to develop zero resistance for the two terminal network, substantially as described.

9. A two-terminal electrical network, including a detecting-amplifying system in said network with mutually non-reacting input and output circuits, both connected to said terminals, with the amplification of said amplifying system adjusted to develop infinity resistance for the two-terminal network, substantially as described.

10. In combination, a transmission line, a generator, and means to allow for an increase in normal line load consisting of a two-terminal electrical network including a push-pull detecting amplifying system with mutually non-reacting input and output circuits and with a second network, balancing the transmission line in mutually non-reactive position with respect to the transmission line, with means to superimpose the final output circuit of the amplifying system upon said transmission line.

11. A two-terminal electrical network with means to automatically change the resistance of said network in response to the variations of alternating current potentials impressed upon the terminals of said network consisting of a detector-amplifying system in said network with mutually non-reacting input and output circuits.

In testimony whereof I affix my signature.
MIHRAN M. DOLMAGE.
